UNITED STATES PATENT OFFICE.

CHARLES BERGERER, OF ROCHESTER, NEW YORK, ASSIGNEE, BY DIRECT AND MESNE ASSIGNMENTS, OF ONE-HALF TO C. T. HAM MANUFACTURING COMPANY, OF ROCHESTER, NEW YORK, AND ONE-HALF TO R. E. DIETZ COMPANY, OF NEW YORK, N. Y., A CORPORATION.

TUBULAR LANTERN.

1,072,688.

Specification of Letters Patent. Patented Sept. 9, 1913.

Application filed March 30, 1909. Serial No. 486,806.

To all whom it may concern:

Be it known that I, CHARLES BERGERER, a citizen of the United States, residing at Rochester, in the county of Monroe and State of New York, have invented a new and useful Improvement in Tubular Lanterns, of which the following is a specification.

This invention relates to the devices which are employed for raising and lowering the globe in the tubular lantern frame and more particularly to that class of lifting mechanisms which comprise a transverse shaft journaled in the tubular frame and connected with a vertically movable globe-supporting frame, the shaft being provided at one end with an arm or lever which engages a catch plate on the tubular frame.

The invention has for its object to render these devices simple in construction and satisfactory and convenient in use.

In the accompanying drawings, consisting of two sheets: Figure 1 is a front elevation of a tubular lantern provided with these improvements, the parts being shown in their normal position. Fig. 2 is a fragmentary sectional view at right angles to Fig. 1, showing the globe plate tilted. Fig. 3 is a horizontal section in line 3-3, Fig. 1. Fig. 4 is a rear elevation of the lantern. Fig. 5 is a horizontal section, on an enlarged scale, through the air tubes, and a top plan view of the lifter shaft and connecting parts. Fig. 6 is a fragmentary perspective view of the lower portion of the lantern showing the globe plate elevated. Fig. 7 is a perspective view of the catch plate. Fig. 8 is a horizontal section through one of the air tubes showing a modified arrangement of the end bearing of the lifter shaft.

Like reference characters refer to like parts in the several figures.

A represents the base portion of the lantern containing the oil pot 10, air chamber 45 11 and burner 12, B the side tubes, and C the central tube, these parts forming the rigid lantern frame.

D represents the globe.

E represents the globe plate, F the bell or canopy which is vertically movable on the central tube, G the annular spring catch secured to the bell and engaging the top of the globe, and H the side wires connecting the

bell with the globe plate. These parts constitute a globe-holding frame which is vertically movable in the lantern frame toward and from the burner. The globe plate is movably connected with the side wires in the usual way to permit the plate to be tilted in inserting and removing the globe.

I represents the guard which is secured to the globe plate and consists, preferably, of two bows 13 which are inclined in opposite directions and cross each other. Each bow is provided with a longitudinally flattened or depressed portion 14, Figs. 2 and 3, against which the side wires bear and whereby the side wires are steadied between their upper and lower ends, the guard bows forming a somewhat yielding or springy intermediate support for the side wires. These depressed portions of the guard keep the side wires in contact with the guard and are so long that the globe plate can be tilted with the guard as far as necessary for conveniently inserting or removing the globe, as illustrated in Fig. 2, without separating or disengaging the side wires from the flattened or depressed side portions of the guard.

K represents the cranked or bent lifter shaft which is journaled in the lantern frame and has its middle portion 15 connected with the globe plate on the rear side of the lantern by a hinge or sleeve 16. L represents the catch plate which is secured to the lantern frame and with which the lifting arm or lever 17 formed on one end of the lifter shaft engages. This plate is arranged on the inner side of one of the air tubes, as shown in Figs. 1-7, and is secured to the tube, preferably by attaching arms 18 which project from the outer edge of the plate through slots in the tube into the interior thereof and are curved to rest with their convex faces against the interior surface of the tube, as represented in Fig. 5.

The catch plate is provided with an upright face 19 which is turned outwardly and against which the lifting lever bears, this face terminating in locking recesses 20, 21, at its upper and lower ends. The plate is provided with a rearwardly projecting ear or lug 22 in which the adjacent portion of the lifter shaft is journaled. The opposite end of the shaft is journaled in a bearing 23

which is secured to the adjacent air tube and preferably provided with an attaching arm 24 which projects into the tube through a slot and is curved to bear with its convex face against the interior surface of the tube, as represented in Fig. 5. This end of the shaft is provided with a short arm 25 which bears against the outer side of this bearing. If desired, however, this end of the shaft 10 may be provided with a reversely bent pivot 26 which is journaled in an opening formed in the outer side of the tube and provided with a bushing or eyelet 27, as represented in Fig. 8.

15 The lifter shaft K and its lever 17 are formed of wire which is somewhat elastic and the shaft is of such length that the lever 17 and the arm 25, on opposite ends of the shaft, bear by reason of this expansible character of the shaft, respectively, against the catch plate L and the end bearing 23 with an inward pressure, which holds the lever against the face of the plate. The inward pressure which is so exerted by the expansible shaft against the plate and the bearing also presses the attaching arms of these parts against the interior surfaces of the tubes and holds the arms in close contact with the tubes.

20 30 I claim as my invention:

1. The combination with a lantern frame and a globe-holding frame movable up and down therein and comprising a bottom member upon which the globe rests and upright side members, of a guard secured to said bottom member and having flattened side portions which bear against said side members between the ends thereof, substantially as set forth.

2. The combination with a lantern frame and a globe-holding frame movable up and down therein and comprising a top member, side members secured thereto and a bottom member having a tilting connection with the side members, of a guard secured to said bottom member and having flattened side portions which bear against said side members between the ends thereof, substantially as set forth.

3. The combination with a lantern frame and a globe-holding frame movable up and down therein and comprising a bell, side wires secured thereto and a globe plate movably connected with the side wires, of a guard secured to the globe plate and having flattened side portions which bear against the side wires above the lower ends thereof, substantially as set forth.

4. The combination with a lantern frame and a globe-holding frame movable up and down therein and comprising a top member, side members secured thereto and a bottom member having a tilting connection with the side members, of a guard secured to said bottom member and having depressed side

portions which bear against the side members above the lower ends thereof, substantially as set forth.

5. The combination with a tubular lantern frame and a globe support movable up and down therein, of a flexible transverse lifter shaft connected with said globe support and provided with a lifting lever which is arranged on the inner side of one of the side tubes, and a catch plate secured to said tube on the inner side thereof and having an outwardly turned locking face against which said lever bears with an inward pressure, substantially as set forth.

6. The combination with a tubular lantern frame and a globe support movable up and down therein, of a transverse lifter shaft connected with said globe support, and a bearing for said shaft provided with a horizontal curved attaching arm which extends into the tube and is arranged with its convex side against the inner surface of the tube, substantially as set forth.

7. The combination with a tubular lantern frame and a globe support movable up and down therein, of a transverse lifter shaft connected with said globe support and provided with a lifting lever, and a catch device against which said lever bears and which is arranged on the inner side of one of the tubes and provided with a horizontal curved attaching arm extending into the tube and bearing with its convex side against the interior surface thereof, substantially as set forth.

8. The combination with a tubular lantern frame and a globe support movable up and down therein, of a transverse lifter shaft connected with said globe support and provided with a lifting lever, and a catch plate arranged on the inner side of one of the tubes and provided with an outwardly turned face against which said lever bears and with horizontal curved attaching arms arranged above and below said face and extending into said tube and bearing with their convex sides against the inner surface of the tube, substantially as set forth.

9. The combination with a tubular lantern frame and a globe support movable up and down therein, of a catch plate projecting inwardly from the inner side of one of the tubes and having at its inner edge a bearing lug formed integrally with said plate, and a transverse lifter shaft and lever connected with said globe support, said shaft being journaled in said lug and engaging with its lever against said catch plate, substantially as set forth.

10. The combination in a tubular lantern frame having a globe, of an air tube, a cranked globe lifter, and a bearing for an end of the lifter comprising a channel shape body the legs of which are secured to the air tube so that the channel faces the tube,

said body having an inturned lifter-locking flange.

11. The combination in a tubular lantern having a globe, of an air tube, a cranked globe lifter, and a bearing for an end of the lifter comprising a channel shape body the legs of which are secured to the air tube, said body having an inturned lifter-locking flange adjacent the bearing of the lifter in said body, the flange having its edge inclined to act as a wedge or cam on the lifter whereby when operated the latter is moved longitudinally and then reversely under said flange.

12. The combination with a lantern tube, globe, and lantern-globe-lifter, of a bearing for an end of said lifter comprising a channel shape body the channel of which faces said tube, said body having an opening for the lifter adjacent a corner of the body, and a lifter-locking part.

13. The combination in a tubular lantern, with a cranked lantern-globe-lifter, of a

support for an end thereof comprising a single body secured to a tube of the lantern, 25 a lifter bearing therein at a distance at one side of said tube, said body having also between said bearing and said tube a lifter-holding part projecting toward the side tube and under which the lifter can pass when the globe is raised.

14. The combination in a tubular lantern, with a cranked globe-lifter, of a support for an end thereof comprising a single body secured to a tube of the lantern, having a 35 lifter-bearing therein, and having also between said bearing and tube a lifter-holding part curving toward and then from said tube over and under which the lifter can pass when the globe is raised. 40

Witness my hand in the presence of two subscribing witnesses.

CHARLES BERGENER.
